UNITED STATES PATENT OFFICE.

CARL P. ASTROM, OF EAST ORANGE, NEW JERSEY, ASSIGNOR TO M. H. TREADWELL COMPANY, A CORPORATION OF NEW YORK.

DUMPING-CAR.

1,118,094.

Specification of Letters Patent.

Patented Nov. 24, 1914.

Application filed January 25, 1913. Serial No. 774,128.

To all whom it may concern:

Be it known that I, CARL P. ASTROM, a citizen of the United States, residing at East Orange, in the county of Essex and State of New Jersey, have invented certain new and useful Improvements in Dumping-Cars, of which the following is a full, clear, and exact specification.

This invention relates to dumping cars, and has particular reference to the construction of a dumping car of considerable length for transporting dry and bulky materials such as ashes, and which can be readily dumped preferably by a tilting and lateral movement without distorting the car body, and also permitting the parts of the car body to be renewed where necessary.

Heretofore, the length of dumping cars having the motor at one end has been restricted because when the length became excessive, the car body would tend to twist and become distorted, ultimately breaking apart. The result has been that only car bodies of comparatively short length and small capacity have been built with the motor at one end, to transport dry and bulky materials.

It is the object of this invention to overcome these difficulties and to provide a car body which can be of considerably greater length and greater capacity than those heretofore built, and which will carry a comparatively large quantity of light material. In order to accomplish this, I propose to construct a tilting laterally moving car frame operated by a motor located at one end in such manner that one end of the body will not be twisted relatively to the other when the motor operates, that is to say, the power will be substantially applied to both ends of the car body at once, thereby eliminating torsion even in a long body.

The invention will be more fully understood in connection with the accompanying drawings wherein—

Figure 1 is an elevation of a dumping car embodying the invention, and Fig. 2 is a perspective view partly in section showing the details of construction.

1 represents an under-frame carrying

cross frames 2, at each end and wheel trucks 3.

4 represents a fluid pressure operated reciprocating motor having a fluid cataract or dash-pot cylinder 5 for controlling the reciprocation, the movable element of the motor being connected by means of a trunnion 6 to a rolling gear 7 supported by a track 8. At the opposite end is provided a similar gear 7 and track 8, these two gears and tracks serving to support both ends of the body so as to move in synchronism. Moving with the gears 7 are rolls 9 supported on tracks 10 carried by the cross frames and taking the weight of the car body. The rolls 9 also constitute end plates as 11, of the car body, these being connected by side frames 12 as shown in Figs. 1 and 2, so that the two end plates 11 and two side frames 12 constitute a rigid tilting and laterally moving frame supported at each end on the cross frames 2 by the roll portions 9.

The mechanism by which the motor is connected to actuate the car body is not a part of this invention, but is shown and described in Patent No. 889,886 dated June 2, 1903, and the preferred form of fluid checking mechanism for controlling the movement of the car body is shown in Patent No. 882,129 dated March 17, 1908.

The power is transmitted from one gear 7 to the other gear 7 through a central shaft 13 extending from one gear to the other, and located between the side bars 12 as shown in Fig. 2, the shaft being rigidly keyed to the gears and to the end plates 11. The bottom of the car body is formed of W-shaped plates 16, which are bent downward and then upward so as to clear the shaft 13, these plates being provided with feet 17, 18 which rest on the flanges 18 of the outer side frames 12. The plates 16 are secured to the side bars 12 by means of links 19, and are themselves braced by rods 20, the slant being such as to secure maximum capacity and still permit the material to slide out in dumping. It will be observed that the side bars are bent upwardly at the ends so as to clear the trucks and to keep the center of gravity of the car when loaded as low as 100

possible. To coincide with this bend there will be a specially formed bottom plate 21 adjacent each end plate. The side bars 12 are secured to lugs 22 carried by the end plates 11, and of course, additional bracing could be used to stiffen this rectangular frame if necessary.

By this invention, a tilting and laterally movable car frame of considerably greater length than has heretofore been built can be produced because the torsion is taken by the central shaft and relieved from the car frame, which latter only takes the strains due to the load.

15 The angle of bending of the bottom plates will be determined according to the angle of the car body when moved outwardly and tilted, being preferably made so that the material can slide freely by gravity out of the body. In case of burning out, breakage or other damage of any one of the plates 16, a new one can readily be substituted without considerable expense and without keeping the car out of operation for too long a time. It will also be observed that the shaft will not be subjected to extremes of temperature, because beneath and separated from the car body, which is a particular advantage when the car is used for transporting hot ashes, slag, etc. Also, it will be seen that the bottom sections can expand and contract independently, by reason of the link connections, without straining the frame or the shaft.

35 Various modifications and changes may be made in the specific construction herein set forth without departing from the scope of the invention.

Having thus described my invention, what 40 I declare as new and desire to secure by Letters Patent is:—

1. A dumping car comprising an under frame, and a dumping car body supported thereon comprising a frame made up of 45 sides and supporting ends, and bottom plates carried by the sides.

2. A dumping car comprising an under frame, a laterally dumping car body supported thereon at the ends, said body comprising end plates resting on the under frame, side frames connecting the end plates, bottom plates carried by the side frames, the end plates extending below the bottom plates and having curved surfaces 55 constructed to roll on the under frame, and means for applying power to move said body.

3. A dumping car body comprising supporting end plates having the lower surfaces 60 curved to constitute rolling supports, side plates connected to said end frames, and transversely extending bottom plates separately carried by said side frames.

4. A dumping car body comprising sup-

porting end plates having their lower surfaces curved to constitute rolling supports, side frames connected to said end plates laterally of said curved supporting portions, and transversely extending depressed bottom sections separately carried by said side 70 frames.

5. A dumping car body comprising supporting end plates having their lower surfaces curved to constitute rolling supports, side frames connected to said end plates 75 laterally of said supporting portions, an actuating shaft extending through said end plates for operating the body, and bottom plates carried by said side frames and overlying said shaft.

6. A dumping car body comprising supporting end plates having their lower surfaces curved to constitute rolling supports, side frames connected to said end plates laterally of said supporting portions, an actuating shaft extending through said end plates for operating the body, and W-shaped 85 bottom plates carried by said side frames and overlying said shaft.

7. A dumping car body comprising supporting end plates having their lower surfaces curved to constitute rolling supports, side frames connected to said end plates laterally of said supporting portions, and a sectional W-shaped bottom between said end 95 plates carried by said side frames.

8. A dumping car body comprising supporting end plates having their lower surfaces curved to constitute rolling supports, side frames connected to said end plates laterally of said supporting portions, and a sectional W-shaped bottom between said end 100 plates carried by said side frames, said bottom sections being linked to said side frames.

9. A dumping car body comprising supporting end plates having their lower surfaces curved to constitute rolling supports, side frames connected to said end plates laterally of said supporting portions, an actuating shaft extending through and secured to said end plates, gears carried by the shaft at the ends, one end of said car body being adapted to be connected to a motor, and a box bottom composed of sections carried by said side frames and overlying said shaft.

10. The combination with an underframe, of a tilting car body supported at its opposite ends on said under-frame, a shaft carried by said car body, a gear at each end of 120 said shaft meshing with said underframe, and an actuating motor connected to one of said gears, whereby power is simultaneously applied at both ends of said car body to actuate it without torsional straining.

11. A dumping car body comprising supporting end plates having their lower surfaces curved to constitute rolling supports,

side frames rigidly connected to said end plates laterally of said supporting portions, and a bottom composed of transverse sections between said end plates, the sections 5 of said bottom being linked to said side frames, to permit independent expansion of the bottom sections.

In testimony whereof I affix my signature in presence of two witnesses.

CARL P. ASTROM.
